EXTRACTIVE DISTILLATION OF TETRAFLUOROETHYLENE WITH AN OXYGENATED HYDROCARBON

Herbert Albert Wiist, Vienna, W. Va., assignor to E. I. du Pont de Nemours and Company, Wilmington, Del., a corporation of Delaware

No Drawing. Filed Feb. 6, 1963, Ser. No. 256,520
6 Claims. (Cl. 203—60)

The process of the present invention relates to the separation of fluorocarbons, and, more particularly, to the extractive distillation of tetrafluoroethylene.

One of the preferred methods of preparing tetrafluoroethylene is by pyrolysis of chlorodifluoromethane at temperatures above 700° C., as disclosed in greater detail in U.S. 2,551,573, issued to Downing et al. on May 8, 1951. The Downing et al. method results in the production of a large number of fluorocarbons in addition to tetrafluoroethylene. These compounds include hexafluoropropylene, perfluorocyclobutane, trifluoromethane, difluoromethane, chlorotrifluoromethane, perfluoroisobutylene, dichlorodifluoromethane, chlorotrifluoroethylene, dichlorotetrafluoroethane, chlorotetrafluoroethane, chlorohexafluoropropane, a homologous series of compounds

(*n* up to 13) and a number of other compounds which have not been completely identified. In another method, tetrafluoroethylene is produced by pyrolysis of bromodifluoromethane. Similar to the pyrolysis of the chlorine analog, the pyrolysis of the bromodifluoromethane produces a large number of fluorocarbons in addition to tetrafluoroethylene. As in the case of the chlorodifluoromethane, the pyrolysis contains a number of compounds which form azeotropes with tetrafluoroethylene or boil so close to tetrafluoroethylene that separation by direct distillation is difficult.

It is, therefore, one of the objects of the present invention to separate tetrafluoroethylene from fluorocarbons by a simple, economic and novel method. It is another object to separate pure tetrafluoroethylene from products obtained by the pyrolysis of chlorodifluoromethane and bromodifluoromethane.

In accordance with the present invention, tetrafluoroethylene is separated from volatile non-perfluorinated fluorocarbons, which, in addition to fluorine, contain at least one element selected from the class consisting of hydrogen and halogens having atomic numbers from 17 to 53 inclusive by extractive distillation. Compounds causing the separation of tetrafluoroethylene from the close boiling or azeotrope forming fluorocarbons are oxygenated hydrocarbons, such as alcohols, ethers, ketones and esters having the general formulas

where R_1 to R_7 are saturated aliphatic or aromatic hydrocarbon radicals, which are liquid at distillation conditions, and, in particular, those which contain up to 12 carbon atoms. The process of the present invention is based on the discovery that the volatility of fluorocarbons boiling close to tetrafluoroethylene, which generally have from 1 to 2 carbon atoms, or form azeotropes with tetrafluoroethylene, is so changed by the addition of the extractive distillation agents of the present invention, that the separation of these groups of compounds becomes a matter of simple distillation. Additionally, it was surprisingly found that these oxygenated hydrocarbons do not react with the reactive fluorocarbons separated by

the process of the present invention, such as tetrafluoroethylene.

Examples of azeotropes of perfluorocarbons and fluorocarbons separated by the extractive distillation of the present invention are tetrafluoroethylene and difluoromethane, and tetrafluoroethylene and trifluoromethane. Most of the close boiling fluorocarbon and perfluorocarbon compounds will be apparent from any table listing the physical properties of fluorocarbon and perfluorocarbon compounds, an example of which is pentafluoroethane and tetrafluoroethylene.

The process of the present invention is of particular utility in combination with processes for the preparation of tetrafluoroethylene, which is prepared by the pyrolysis of chlorodifluoromethane, bromodifluoromethane or by inorganic and organic fluoride arc processes known in the art.

The addition of the above-described extractive distillation agents was found to rearrange the volatilities of the interfering fluorocarbons in such a manner as to greatly enhance the volatility of the tetrafluoroethylene, thereby preventing the formation of the undesirable azeotropes and also preventing the distillation of close boiling fluorocarbons. The preferred extractive distillation agents of the present invention are volatile hydrocarbon alcohols, ethers, esters and ketones which are liquid under distillation conditions and include methanol, ethanol, propanol, isopropanol, butanol, isobutanol, tert-butyl alcohol, decanol, phenol, benzyl alcohol, o-cresol, dimethyl ether, diethyl ether, methyl ethyl ether, methyl propyl ether, methyl phenyl ether, ethyl benzyl ether, acetone, methyl ethyl ketone, diethyl ketone, acetophenone, propiophenone, methyl acetate, ethyl formate, methyl propionate, ethyl acetate, propyl formate, etc. The quantity of the extractive distillation agent to be employed can be varied over a wide range. Even the addition of small quantities of the extractive distillation agent will significantly affect the volatility. In order to readily facilitate the separation of the higher boiling fluorinated hydrocarbons obtained from the pyrolysis, after removal of starting material and tetrafluoroethylene it is preferred to employ from 1 to 25 times the weight of the extractive distillation agent as compared to the weight of the higher boiling fluorocarbons.

Relative volatilities at atmospheric pressure of fluorocarbons forming azeotropes with tetrafluoroethylene are shown in Table I using mixtures comprising 3 parts of the indicated extractive distillation agent and 1 part of the fluorocarbon. Tetrafluoroethylene is taken as the most volatile component.

TABLE I

Extractive Distillation Agent	Difluoromethane	Fluoroform
Acetone.....	19.3	7.8
Methanol.....	9.9	4.25
Diethyl ether.....	4.65	3.16
Ethyl acetate.....	11.8	—

60 The effect of the concentration of the extractive distillation agent on relative volatility at atmospheric pressure is shown in Table II. Tetrafluoroethylene is again taken as the most volatile component.

TABLE II

Wt. of acetone/wt. of fluorocarbon:	Difluoromethane
0.5	5.4
1.0	9.3
2.0	15.9
3.0	19.3

70 Relative volatilities of a tetrafluoroethylene, fluoroform, difluoromethane mixture were determined using

acetone as the extractive distillation agent. The mixture contained 64 parts of tetrafluoroethylene, 26 parts of fluoroform and 10 parts of difluoromethane. The ratio of acetone to the fluorocarbon mixture was 1:1.4. The relative volatilities were determined at a pressure of 125 p.s.i.a. It was determined that tetrafluoroethylene was 2.66 times as volatile as fluoroform and 3.78 times as volatile as difluoromethane.

The relative volatilities of the components of the mixture illustrated in the tables below were determined using acetone as the extractive distillation agent. In the determination illustrated in Table III, a pressure of 125 p.s.i.a. and a temperature of 63.5° C. were employed. The mole percentage of acetone in the liquid was 79.0 and the mole percentage of acetone in the vapor was 10.3. In the determination illustrated in Table IV, a pressure of 60.5 p.s.i.a. and a temperature of 76.8° C. were employed. The mole percentage of the acetone in the liquid was 93.0 and the mole percentage of the acetone in the vapor was 15.9.

TABLE III

Component	Mol Percent		Relative Volatility ¹
	Liquid	Vapor	
Tetrafluoroethylene	11.14	31.53	
Chloropentafluoroethane	5.48	9.60	1.62
Hexafluoropropylene	2.86	3.56	2.27
Trifluoromethane	19.0	23.71	2.27
Pentafluoroethane	20.26	12.24	4.70
Chlorodifluoromethane	33.08	10.95	8.50

¹ Tetrafluoroethylene is taken as the most volatile component.

TABLE IV

Component	Mol Percent		Relative Volatility ¹
	Liquid	Vapor	
Tetrafluoroethylene	1.66	4.84	
Chloropentafluoroethane	6.04	13.68	1.29
Hexafluoropropylene	3.24	5.47	1.75
Trifluoromethane	23.42	31.84	2.16
Pentafluoroethane	21.82	18.23	3.52
Chlorodifluoromethane	34.96	14.53	7.1

¹ Tetrafluoroethylene taken as the most volatile component.

Example I

Crude tetrafluoroethylene, having the following composition.

	Mol percent
Tetrafluoroethylene	95
Pentafluoroethane	1
Difluoromethane	4

was fed into a 43" long, 1" diameter packed column (35-40 plates) operating at atmospheric pressure, 25" up from the base at a rate of 200 g./hr. Methanol at -70° C. was fed from the top of the column at 400 g./hr. Reflux was at an approximate ratio of 1:1. Temperature of the column ranged from +20° C. at the base to -76° C. at the top of the column. Analysis of the overhead showed the product to be greater than 99.90% pure tetrafluoroethylene. The same results are obtained when a bromodifluoromethane pyrolysate containing 5 to 20 mol percent of difluoromethane and 0.1 to 0.2 mol percent of pentafluoroethane is employed.

Example II

Crude tetrafluoroethylene, having the following composition

	Mol percent
Tetrafluoroethylene	94.7
Trifluoromethane	3.2
Difluoromethane	0.4
Pentafluoroethane	0.3
Chloropentafluoroethane	0.1
Chlorodifluoromethane	1.1
Hexafluoropropylene	.2

was fed vapor phase into a 43" long, 1" diameter packed column (35-40 theoretical plates) operating at atmospheric pressure, 25" up from the base at a rate of 400 g./hr. Acetone at -70° C. was fed from the top of the column at 600 g./hr. Reflux was at an approximate ratio of 1:1. Temperature of the column ranged from -76° C. at the top of the column to +31° C. at the base. Purity of the tetrafluoroethylene removed overhead was greater than 99.9 mol percent.

The process of the present invention provides a simple, effective and economic method for the recovery of pure tetrafluoroethylene when formed in admixture with other fluorocarbons, such as are obtained in the pyrolysis of chlorodifluoromethane and bromodifluoromethane.

I claim:

1. A process for separating tetrafluoroethylene from fluorocarbons containing from 1 to 2 carbon atoms and, in addition to fluorine, elements selected from the class consisting of hydrogen and halogen, having atomic numbers from 17 to 53 inclusive in admixture with the tetrafluoroethylene, the steps of distilling the mixture, by extractive distillation in the presence of an oxygenated hydrocarbon, liquid at distillation conditions and selected from the class consisting of alcohols, ethers, ketones and esters, said oxygenated hydrocarbons having the general formulas R_1OH , R_2OR_3 , R_4COR_5 and R_6COOR_7 , where R_1 to R_7 are radicals selected from the class consisting of saturated aliphatic and aromatic hydrocarbon radicals, and removing the tetrafluoroethylene as an overhead from the distillation zone.

2. The process of claim 1 wherein the extractive distillation agent is a ketone containing 1 to 12 carbon atoms.

3. The process of claim 1 wherein the extractive distillation agent is an alcohol having 1 to 12 carbon atoms.

4. The process of claim 1 wherein the extractive distillation agent is an ester having 1 to 12 carbon atoms.

5. The process of claim 2 wherein the ketone is acetone.

6. The process of claim 1 wherein the tetrafluoroethylene is separated from a compound of the class consisting of difluoromethane, pentafluoroethane, fluoroform and chloropentafluoroethane.
